FIG - 14

AUTOMATIC MACHINE FOR THE CONDITION OF CIGARETTES INTO PACKETS

This invention relates to an automatic wrapping and packing machine for conditioning cigarettes in packets, by means of which it is possible, starting from loose cigarettes, to achieve, through a succession of work phases, finished and sealed packets of cigarettes, in which, moreover the presence of defective packets between those produced by the machine is excluded.

Automatic machines for the manufacture of packets of cigarettes, are well known, in which the cigarettes themselves proceed through the successive phases of their conditioning and are maintained with their longitudinal axis oriented according to the direction of advancement, while the formation of the envelopes with successive layers of packing material, occurs, either directly on the body of the cigarettes, which act therefore as mandrels, or by folding said layers of packing material, completing also the base of the envelope, around a fixed mandrel constituted of a tubular member, inside which the batch of cigarettes is pushed in the direction of the axis of the cigarettes themselves, which thus push against the base of the envelope in order to pull it away from the fixed mandrel about which the same envelope has been formed.

It happens thus that the cigarettes are continually stressed, particularly in the sense of their longitudinal development, that is at their tips. In fact, in all the work phases both those relative to the formation of the envelope and those of simple transfer between the successive conditioning stations the cigarettes are submitted to axial stresses which inevitably determine a decadence of their characteristics; in particular the stresses produce crumpling and folding, on the papers of the cigarettes, while the tobacco contained inside the cigarette papers, becomes less compact. Such machines, moreover, because of the time required for the successive operations, as well as of considerable masses subjected to reciprocal motions, or for still other reasons, are constrained as to speed of working, and thus to productions per unit time, which are often noted to be insufficient, and in any case limited.

A principal object of the present invention is that of obviating such inconveniences by offering a machine operated so that the cigarettes are arranged, during the conditioning into packets, so as not to suffer axial stresses. Moreover, always with the intention of not stressing the cigarettes, in particular at their tips, the batches of cigarettes are designed to constitute single packets and are constantly contained, protected, and guided either by and within certain surfaces or by holding and supporting means in general so as also to maintain the batches perfectly compact and already conformed in the arrangement in which they will be packed.

A further object of the present invention is that of providing a conditioning machine for packaging cigarettes, which may work at high speed and produce notably superior productions of packets per unit time to those of the machines generally used in this field.

Consequently, according to one of the characteristics of the invention, the automatic machine for the conditioning of the cigarettes in packets comprises members for the formation of successive batches of cigarettes, arranged in side by side and superimposed arrangement in said batches, means for the transfer of said batches to the conditioning line comprised of a plurality of stations for packing said batches, apparatus for the feeding of said stations with packing materials, folding members for the formation of the envelopes from said materials, characterized in that said stations comprise moving means capable of translating the successive batches of cigarettes transversely to their own axes, support and guide means succeeding each other within each station and between successive stations for supporting and constantly accompanying said batches, said folding members producing the forming of the envelopes on the batches with the interposition of said guide elements operating on said batches act as mobile mandrels.

More particularly, having reference to one of the possible embodiments, said machine comprises a hopper for keeping

the loose cigarettes and distributing them intermittently in fixed quantities, to form successive batches of cigarettes, forwarding them on a conveyor means. The batches thus formed correspond, in number and in arrangement of the cigarettes in superimposed layers, to the single packets which will be produced by the machine. Such batches are arranged on conveyor means, with orthogonal orientation with respect to the direction of the advancing motion of the conveyor means, so as to be moved transversely to their own shaft. The conveyor means transfer the successive batches of cigarettes, with an intermittent advance, in correspondence with a removal station for the batches themselves for their forwarding to a line constituted of varied and successive conditioning stations of the packets. The batches of cigarettes are thus conditioned into packets, which, making reference to a packet of the so-called "American" type (i.e., a flexible packet as opposed to a "crushproof" packet), comprising in general a first internal layer tinfoil, and a second external layer of paperlike material constituting the so-called label; the packet is finally sealed by a stamp or sealing tape. Thus in relation to this, the machine according to the invention also comprises an apparatus for the feeding, to the conditioning line, of successive cutdown pieces of tin foil, a further apparatus for the feeding of successive labels, and finally an apparatus for the distribution of successive sealing tapes.

Advantageously an apparatus may be provided, situated at the exit of the conditioning machine according to the invention, for effecting the drying of the envelopes, relatively to their glued areas.

Further characteristics and advantages will be better apparent from the description of an automatic machine according to the invention, illustrated, by way of indication and not intended to be limiting, in the accompanying drawings in which:

FIG. 1 shows diagrammatically a perspective view of the assembly of the machine illustrating the relative positions of its parts, and with the exclusion of those parts situated in the end section of the conditioning line;

FIGS. 2 and 3 show, read in succession, a perspective diagram of the formation line of the packets leaving the batches of cigarettes already formed;

FIGS. 4 and 6 show, part in view and part in vertical longitudinal sections according to different planes, the members relative to the formation line of the packets leaving the batches of cigarettes;

FIGS. 5 and 7 show, part in view and part in vertical cross sections according to different planes, the same members respectively of FIGS. 4 and 6, said views 5 and 7 comprising right-end views with respect to FIGS. 4 and 6;

FIG. 8 shows an electromechanical diagram of the connection of all the members controlled by the sensitive elements for the removal of the defective batches of cigarettes;

FIGS. 9a and 9b illustrate a diagram of the working phases of the principal movable members of the machine, in normal conditions and in which the phases expressed in degrees are represented by abscissas, and the qualitative progress of the movements by ordinates;

FIG. 10 shows, in magnified scale, a detail of a station of the conditioning line of the packets, according to a plane view;

FIGS. 11 and 12 show, according to sectional views an orthogonal elevation between them a detail of another station of the formation line of the packets;

FIG. 13 shows, in lateral section view, a detail according to a variation of a station of the formation line of the packets, situated upstream from the stations which refer to details of the preceding FIGS. 10, 11, and 12; and

FIG. 14 shows the configuration of holding arms of one of the folding stations.

In the embodiment of the machine represented in the above-mentioned drawings, some parts and apparatus are briefly indicated inasmuch as they are better described in applicant's issued U.S. Pat. No. 3,520,394. Thus in FIG. 1 is indicated with reference numeral 1 a hopper mounted cantil-

everwise on the case 2 of the machine, which in conformity to what has been stated in detail in the issued U.S. Pat. No. 3,520,394 of the same applicant, is intended to feed with superimposed side-by-side layers of cigarettes the compartments 3 of a transport chain 4 advancing intermittently and motorized for example by the principal shaft of the machine in the manner according to said issued U.S. Pat. No. 3,520,394.

In relation to the mentioned possibility that one of the said batches might be defective either because of a lack of one or more cigarettes, or because cigarettes are presented insufficiently filled with tobacco, along the run of the chain 4, the presence of groups 5 of sensing members of known type is provided for the sensing of such defects. These sensing members determine the control of an expeller member 6 which causes the removal of defective groups, as soon as, in its intermittent advancement, the defective group is moved in the range of said expeller member. It is understood how in such manner a gap in the succession of batches of cigarettes advancing in step is caused to occur, in synchronism with their formation upstream, beneath the hopper 1. The presence of such gaps is evidenced in the influences to the working of other members which will be mentioned later.

When the groups of cigarettes reach the end of the horizontal section of the chain 4, a pusher 7, activated in manner according to said issued U.S. Pat. No. 3,520,394 operates the transfer of the batches themselves from chambers 3 to the line of conditioning proper, situated parallel to said chain, but developing along a middle vertical plane which is retracted with respect to the middle plane of the chain.

In this phase, a transfer of the head of the batch of cigarettes occurs, without endangering the structural configuration and of the cigarettes themselves: in fact, in order to effect the transfer of them, the cigarettes are simply pushed, without opposition, thus without the exercise of any stresses which could be harmful. Because of this, this axial transfer is not in contradiction with the general conception which characterizes the embodiment in its entirety, said concept consisting particularly, as has been said, of the nonstressing of the ends of the cigarettes.

By said pusher means 7 the successive batches of cigarettes are transferred to a position between the pairs of jaws 8 of a wheel with radial pincers. This wheel conforms to what is described in applicant's issued U.S. Pat. No. 3,501,023, and is constituted of pincers of radial development the pair of jaws of each being interdistanced by a space corresponding to the thickness of the batch of cigarettes; said jaws may diverge (spread apart) at the moment of the introduction between them of said batches by means of the pusher 7, a vertical wall element 10 cooperating in this diverging movement, which wall 10 is arranged during the transfer, as provided in the U.S. Pat. No. 3,501,023 of the same applicant, at the end of the pincers. The jaws are thus reclosed for retaining said cigarettes, while the wheel turns simultaneously about the shaft 11 so as to transfer the batches of cigarettes into a diametrically opposite position; finally the jaws open in order to give the batches to successive holding and transfer means. Thus, briefly, it is in this manner that the batches of cigarettes are formed and transferred to the entrance of the conditioning line where they receive the successive layers of paper material for the formation of the packet.

The members operating in the successive stations of the conditioning line will now be described. The principal shaft 12 of the machine, which is mounted on a frame indicated by reference numeral 2, carries some cogwheels 13, 14, and 15, rigidly mounted on it. The cogwheel 13 meshes with a cogwheel 16 on whose shaft 17 is rigidly mounted a cam or revolving drum 18 provided with a pair of diametric idle rollers 19 capable of activating a Maltese cross 20 for the control of the intermittent movement of the pincer wheel 9 in conformity with the above-mentioned U.S. Pat. No. 3,501,023, as shown in FIG. 1 thereof.

A cogwheel 21 engages with the wheel 14 and is rigidly mounted on a shaft 22, perpendicular to the main shaft 12 of

the machine, for rotation with said wheel 14. On said shaft 22 is similarly keyed a disc cam 23 provided with a frontal groove into which engages a roller 24 turning idly about a pin 25 connected to a lever 26. Said lever 26 is pivoted at one end, as at 27, to the fixed framework 2 and at its other end, as at 28, to a vertical rodlike member 29, which slides in a guide 30, and which has a bladed folding member 31 at its upper end. The blade 31 is in such manner associated to provide a vertical reciprocal movement.

10 The wheel 15 engages instead with a cogwheel 32 rigidly mounted on a shaft 33 parallel to the shaft 22, which shaft 33 is thus entrained in rotation. On said shaft 33 is also rigidly mounted a cogwheel 34 which engages with a cogwheel 35 carried by a shaft 36 parallel to the shaft 33, and by a cogwheel 37 carried by a shaft 38 parallel to the latter shafts. The shaft 36 carries, connected with it, a rhomboid cam or revolving drum 39 whose diametrically opposite idle rollers 40 enter into cyclical engagement with the profile of a Maltesecross wheel 41 revolving rigidly with its own shaft 42.

15 20 In a similar manner the shaft 38 carries a cam 43 whose diametrically opposite rollers 44 enter into cyclical engagement with the face of a Maltese cross wheel 45 rigid with its own shaft 46, parallel to the shaft 42. Thus the uniform rotational motion derived from the shaft 12 is transformed into intermittent rotational movement of the parallel shafts 42 and 46.

25 30 On the shaft 42 is keyed a cogwheel 47 which meshes with a cogwheel 48 attached to a shaft 49, while with the shaft 46 is attached a cogwheel 50 which meshes with two cogwheels 51 and 52 which are rigidly mounted on their respective shafts 53 and 54. The shafts 49, 53, and 54 are parallel with each other and lie in a horizontal plane. They are associated, by means of connections already described, to an intermittent rotational movement derived from the uniform rotation of the shaft 12.

35 40 Two matched levers 55 and 55a are attached in their lower sections, through the respective sleeves 56 and 56a, to a transverse common shaft 57. Reference is now made only to lever 55, intending that what is described shall be extended in 40 equivalent manner through the lever 55a.

45 50 In an intermediate section of the longitudinal development of the lever 55 is attached the common shaft of a pair of revolving rollers 58 and 59. Said pair of rollers cooperate with a cam 60 rigidly mounted on the shaft 33 and defining a double eccentric guide, a face guide 61 for the roller 58 and a peripheral guide 62 for the small roller 59 respectively. At the upper end, said lever engages, by the interposition of an articulated link 63, in 64 with a block 65. Two aligned sections 55 55 of a horizontal rod 66 which develops parallelly to the shaft 12 are secured on either side of said block. Through the rotation of the shaft 33, and in consequence of the cam 60, the lever 55 is provided with an oscillating movement about its own axis of rotation 57, so that the rodlike member 66 is similarly subjected to a reciprocal movement of going and coming in the direction of its own shaft. The rod 66 is led, in its longitudinal translational movement by the engagement of the small rollers 67 revolving about their own pins 68 attached to a block 65, inside a longitudinal guide 69.

60 65 70 As has been said, a similar arrangement applies to the lever 55a, therefore the corresponding elements are indicated by the same reference numerals with the addition of the letter *a*. In particular there will be a second rodlike member 66a, parallel and side by side with the member 66, and it also being subjected to a reciprocal movement. The cam 60a is however realized in a manner in which a certain phase displacement exists between the movements of the rodlike members 66 and 66a, as will be better stated below.

75 70 To the rod 66 is attached the support base 70 of a first push translator 71, while to the rod 66a is attached the support base 70a of a second companion pusher 71a designed to cooperate with the member 71. The translator members 71 and 71a, define, at their ends, two holding surfaces, 72 and 72a respectively, parallel between each other and spaced apart by a distance substantially corresponding to the width of the larger

side of the base of the packets of cigarettes. In an analogous manner further push translators, and companions, are carried by the rods 66 and 66a. Thus two other pairs of translators 73 and 73a, 74 and 74a, are located, provided with parallel holding surfaces, 75 and 75a, 76 and 76a, respectively, being analogously spaced apart by the width of a batch or packet of cigarettes.

Moreover a pusher 77 is attached to the end of the said shaft 66.

The profiling of the cams 60 and 60a is such that, as has been said, a certain displacement of phase occurs between their movements. In particular the pairs of pusher members move together until arriving in proximity of the limits of the displacement of the rods 66 and 66a. However, in proximity to the said ends, the inversion of the movement of one of the rods precedes that of the other, so that the pair of holding members open slightly, because of this displacement of phase, permitting the effecting of certain operation of removal and abandonment of the packets of cigarettes, which will be explained in detail hereinafter. The rods 49, 53, and 54 assure the necessary movements to three distinct and successive stations for the folding of the wrapping material, indicated in their entirety by reference numerals 78, 79, 80 (see FIG. 1), and relative to the various phases of the packing of the cigarettes.

The transfer of the batches or packets of cigarettes between said successive stations is obtained by means of the aforesaid translator members, and specifically the pair of members 71 and 71a insert the batch of cigarettes into the station 78, the pair of members 73 and 73a operate the transfer of the batch of cigarettes from the station 78 to the station 79, the pair of translator members 74 and 74a operate the transfer of the batches of cigarettes from the station 79 to the station 80, and finally the push member 77 effects the forwarding of the packet of cigarettes from the station 80 to a successive station which will be described hereinafter.

The three stations 78, 79, and 80 are delimited in their upper sections by covers or semicylindrical guides 81, 82, and 83 coaxial with their relative shaft to each of the said stations. The axial development, or transverse width, of such cover is notably equal to the longitudinal development of a packet of cigarettes.

Essentially each of the said stations 78, 79, and 80 are formed (see FIG. 4) of a device rotating inside the respective semicylindrical covers 81, 82, and 83 and comprises the said corresponding shafts 49, 53, and 54; to each of said shafts is associated a pair of holding members axially spaced apart along the respective shaft, by a distance less than the width of the packet of cigarettes and each formed of two arms which extend parallelly to the diameter of the respective semicylindrical covers which in turn are spaced between each other by a distance substantially equal to the thickness of the packet, thus of the dimension corresponding to that of the superimposed layers of cigarettes forming the batches for packing. The arms of such pairs of holders are indicated in said FIG. 4 by reference numerals 84, 85 and 84a, 85a for the station 78, by reference numerals 86, 87 and 86a, 87a for the station 79 and by reference numerals 88, 89 and 88a, 89a for the station 80. FIG. 14 shows, for example, the shapes of the plates 84, 84a, and 85, 85a, said plates being connected to a shaft 49a, and between them the cigarettes are inserted and gripped by the surfaces 72 and 72a, of the translator members 71 and 71a. This structure is defined in detail in my U.S. Pat. No. 3,501,023. In particular, the translator members such as 71, 71a are capable of holding the cigarettes in a stable batched configuration, between the plates 72, 72a during translation, due to a transverse pressure on the cigarettes exerted by said plates while the cigarettes are held in the jaws 8 and maintained during translation, so that the upper and lower rows of cigarettes in the batch become slightly deformed whereby their abutting surfaces are slightly flattened. Then, the friction resistance between such flattened surfaces prevents the cigarettes from falling away from the grasp of the translator members when the batch of cigarettes is removed from the jaws 8.

The shaft 49 relative to the station 78 entrains in rotation two plates or blades 90 and 91 situated on either side of the semicylindrical profile 81. The plates 90 and 91, whose lengths are substantially equal to the internal diameter of the profile 81, peripherally present flat bands or square sections 92 and 93. Said plates 90 and 91 can be moved in directions opposite to the direction of the shaft 49, so as to pass from a first position, in which they are practically aligned with the vertical planes laterally delimiting the cover 81, and thus spaced apart by a section nearly equal to the longitudinal development of the packet, to a second position in which they are slightly separated, in opposite senses so as to allow the passage of the packet between the end sections of the edges 92 and 93. This reciprocal movement is determined by means of a cam 94 keyed onto the main shaft 12. In the face groove of said cam engages, through the small roller 95, an angled lever 96 pivoted in an intermediate position of its development about a shaft 97, and acting at its opposite end 98 (see FIGS. 5 and 10), endwise on a rodlike member 99 internal and coaxial to the shaft 49, with which it rigidly rotates. Said rodlike member 99 in turn cooperates (see FIG. 10) at the end with the rod 100 extending inside the tubular prolongation 49a of the shaft 49. In FIG. 2 the mechanism is represented schematically but it is shown in greater detail in FIG. 10. In particular in said FIG. 10 it is possible to see that the plate 91 is not in one single piece but, on the contrary, it is formed by two symmetrical plate sections. To one end of said rod 100 is attached the plate 90 by means of the locking member 101, while in proximity to the other end of said rod there is a widened section 102 which cooperates with an end of the two symmetrical plate sections forming the above indicated plate 91. Such plate sections are pivoted in 103 and 104 respectively on a member integral with the tubular prolongation 49a so as to be able to oscillate, against the action of the counter springs 105 and 106, following the axial movement of the rod 100 which is caused by the movement of the rod 99 described above. In this manner it is manifest that corresponding to the axial movements of the rods 99 and 100 spring-biased movements of separation and approach respectively of the plates 90 and 91 occur in such manner as to assume the aforesaid operative positions.

The shaft 53 of the station 79 also carries in rotation a pair of plates 107 and 108 which slide almost flush with the vertical planes laterally delimiting the cylindrical cover 82; said plates are also spaced apart by a distance corresponding to the longitudinal dimension of the packet.

A further folder member 109 acts in the range of one of the vertical planes laterally delimiting said cover 82, said folder member being attached to the upper end of a rodlike member 110, driven by a vertical reciprocal movement due to the engagement of the roller 111, connected to it, inside the groove of a disk cam 112 which is rigidly mounted on the shaft 33. The vertical slidings of the rodlike member 110 are guided by a further roller 113 sliding in a vertical guide 114.

The station 79 is also provided with an attached folder member 115 formed of a circular crown and coplanar with the folder 109, and thus aligned with the same vertical surface delimiting the cover 82. A fixed horizontal plate 116 is moreover carried cantileverwise by the cover 82 at the section opposite to said folder 115.

A folder 117, similar to the member 115, is similarly present in the successive station 80, while the shaft 54 puts a pair of support plates 118 and 119 in intermittent rotation so that said plates, similar to the previous plates, also rotate flush with the vertical planes delimiting the cover 83. At the entrance to said station a folder member functions conventionally as indicated by reference numeral 120.

Said folder is shown according to an embodiment in the FIGS. 11 and 12 and is formed by two symmetrical plates 120a and 120b associated to respective arms 121 and 122 converging to a shaft 123 and to a tubular sleeve 124 respectively, said sleeve being connected to a gear 125. The shaft 123 extends in the interior of the tubular shaft 54 of the station 80 shown in FIG. 4, which shaft rotates, as seen previously, under the con-

trol of the gear 52 inside said tubular sleeve 124. The gear 125 is in mesh with a toothed sector 126 rigidly mounted on the end of a shaft 127 which is revolvingly supported by the fixed body 128 and at its opposite end is rigidly mounted on a second toothed sector 129 which is in mesh with a toothed sector 130 rigidly mounted on said shaft 123. Said sector 130 is provided with a radial projection 131 to which is articulated in 132 an end of a tie rod 133 whose other end is articulated in 134 to the end of one of the arms of a two-armed lever 135 pivoted in 136 to a fixed support 137 supported by the fixed framework 2 of the machine. At the free end of the other arm of said lever 135 is attached in 138 an idle roller 139 capable of cooperating in the groove of a control cam 140 rigidly mounted on said shaft 33. In this manner it is evident that by the oscillating movement of the lever 135 which is caused by the form of the control groove of the cam 140, through the toothed sections 130, 129, 126 and the gear 125, the plates 120a and 120b of the folder 120 are made to oscillate about the shaft of the station 80, and the spacing between said plates permits the arms 74, 74a to move therebetween upon axial movement of the shafts 66, 66a, so that a batch of cigarettes can be translated by plates 76, 76a from station 79 to station 80, whereupon upward movement of the two folding plates folds a portion of the label 172 as shown at station 80 of FIG. 2.

On the aforesaid shaft 33 is also rigidly mounted (see FIG. 5) a cam 141 in whose groove 142 is engaged an idle roller 143 carried at the end of one of the arms of a two-armed lever 144 (see FIG. 4), whose other arm is articulated to a tie rod 145 in order to cooperate in the working of the pincer wheel 9 as described in the U.S. Pat. No. 3,501,023 of the same applicant.

A first fixed die plate 146 is situated immediately in front of the station 78.

Between the conditioning stations 78 and 79 is situated a second fixed die plate 147 while between the stations 79 and 80 is situated a third fixed die plate 148.

On the profiles of said die plates, contours or lateral teeth are present, indicated by reference numerals 149, 150, and 151, respectively, while in the lower section of the die plates are provided with a hole, respectively 152, 153, and 154 capable of permitting, as will be seen hereinafter, the passage of the translator members of the machine.

Naturally said die plates are positioned in alignment with said stations 78, 79, and 80.

The batch of cigarettes G, which arrive at the die plate 146, intersect in their advancement towards the die plate itself, and immediately before this, with the downward trajectory of a cutdown piece of tin foil 155, designed to form the innermost layer of the packet and which descends from a delivery apparatus. This latter may be, for example of the class which provides the subject matter for applicant's issued U.S. Pat. No. 3,495,820 of the same applicant, and is activated by a gear 156 rigidly mounted on the shaft 17 controlled by the main shaft 12 of the machine through the pair of cogwheels 13 and 16, as seen hereinbefore. Said gear 156 is in fact in mesh with a gear 157 rigidly mounted on the shaft 158 and in mesh with the gear 159 rigidly mounted on the shaft 160 pertaining to such apparatus. Said gear 159 is in mesh with a further gear 161 rigidly mounted on the shaft 162 which also pertains to said apparatus, while on the shaft 160 of the same gear 159 is also rigidly mounted a chain wheel 163 which by means of a chain 164 transmits the movement to the chain wheel 165 of a further shaft 166 of the aforesaid apparatus according to the cited U.S. Pat. No. 3,495,820.

Therefore the characteristics and the working of such apparatus will be briefly recalled, with reference to the diagrammatic representation shown in FIG. 1.

It comprises in substance a framework 167 mounted cantileverwise on the body 2 of the machine and above the conditioning line. The continuous strip of tin foil is unwound from a bobbin supported by the shaft 168 and enters the apparatus from above. Provision is made for the arrangement of a

second paper bobbin, mounted on the shaft 169, so as to be able to effect the immediate substitution of a continuous strip, when it is exhausted, by a new strip, without in practice interrupting the working of the machine.

5 In relation to the speeds of production of the packets at which the machine according to the invention is designed to operate it is advantageous to reduce as much as possible the time absorbed by the machine for the operation of folding of the envelopes. For such reason, paper wrapping material before arriving at the conditioning line is previously prearranged inside the distributing apparatus in such fashion that the successive operation of the formation of the envelopes is facilitated.

10 Because of this, in the distribution apparatus according to the cited patent, the continuous strip of tin foil passes through a first pair of guide rollers 170 and then through a second pairs of rollers 171 provided with contoured profiles and with conjugate groovings to said contours, which, corresponding on the surface of the strip of tin foil determine on the strip itself some incisions or groovings in correspondence with the area in which, in the successive operations of formation of the packet proper about the cigarettes, the tin foil is folded in order to form the internal layer of said packet. Thus, in its descent the continuous strip passes in the range of a pair of shears or cutting edges, not visible in the drawing, which perform the cutting of the strip into cutdown sections, each section corresponding to the envelope of a batch of cigarettes, and thus to a packet. The cutdown sections are then entrained

15 towards the lower part of accelerator rollers until they are brought in range with them and immediately before with said first die plate 146, transversally to the line of advance of the batches.

At the exit from the station 79 and immediately before from the die plate 148, the batch of cigarettes, on which has already been superimposed the tin foil, intersects in its advance (always in direction perpendicular to the axis of the cigarettes) the trajectory of a cutdown piece of paperlike material 172 constituting the so-called label, which comes from an opposite distributing apparatus.

This apparatus may be, for example, of the class forming the subject matter of U.S. Pat. Nos. 3,559,617 and 3,495,820 of the same applicant; it is particularly adapted to the distribution at high speed of successive labels, suitably glued.

Therefore the structural and working characteristics of the above will now be briefly described, with reference to the diagrammatic representation of FIG. 1.

In such apparatus, the labels are arranged piled inside a hopper 173 mounted cantileverwise on the framework 2 of the machine and are removed one by one cyclically, from the bottom of the hopper itself by means of a cylindrical sector 174, actuated by a movement composed of rotation about its shaft 175 and of horizontal translation rigidly with the shaft 175 along a slit 176 of the body 177 of the apparatus.

Since the surface of the sector 174 is cyclically positioned in communication with a suction source from a distributor valve according to the cited patent applications, the labels are removed by suction from the surface of the sector 174, and are dispatched, by means of the receiver roller 178 and the guide plates 179, to a gluer unit comprising a tank 180 in which the gluing material is contained. Said tank is hinged in its lower section about a shaft 181 so as to be able to accomplish angular movements about it and inside the said tank a glue roller dips which revolves about the shaft 182 supported by the shoulders of the tank; said glue rollers transmits the glue, through the small roller 183 onto the surface of the label in transit according to the aforesaid patent applications.

The station 80 is followed by a further packet transfer station, indicated in its entirety with reference numeral 184 (see FIGS. 2, 3, 6 and 7). It comprises in substance a wheel 185 defining a plurality of radial compartments 186 having practically the form of the packets for transfer. Said wheel, whose shaft 187 is parallel to those of said stations 78, 79, and 80 and is coplanar with them, rotates inside a semicylindrical lower

cover 188 and semicylindrical upper guide 189 for a plurality of plates 190 rigid with the wheel itself in the range of the rear aperture of the compartments 186 and whose function is explained hereinafter. Said covers 188 and 189 in the range of the ends of the horizontal diameter of the wheel 185 are spaced apart by a corresponding section 191 and 192 equal to the thickness of the packet in order to permit the introduction in, and the radial removal of the packets from, said wheel 185. The cover 188 extends moreover, from the aperture 191 to define a horizontal bracket 188a which extends to the proximity of the shaft of the station 80 and along which is obtained a groove 188b in order to permit the passage of the pusher 77, in an analogous manner, from the part opposite is situated a bracket 188c.

The wheel 185 is subjected to an intermittent rotational movement, in step with the intermittent advance movements of the packets of cigarettes along the conditioning line. This is obtained in the following manner: the motion is derived from the shaft 193 of the electric motor 194 supported in known manner by the framework of the machine and, through the reduction pulleys with movable members of known class 195 and the belt 196 motorizes a pulley 197 which couples, by means of a spring-biased front clutch of the conical engagement nib type 198, with a disk 199 rigidly mounted on the principal shaft 12 of the machine, which is consequently entrained in rotation. On the shaft 12 is rigidly mounted a cogwheel 200 which engages with a wheel 201 attached to a shaft 202, which develops horizontally and orthogonally with respect to said shaft 12. The shaft 202 similarly entrains a cogwheel 203 in rotation, said cogwheel interlocking with the wheel 204 which is rigid with the shaft 205, and causing in turn the rotation of it. On the shaft 205 a rhomboid cam 206 is rigidly mounted, said cam turning with uniform motion, engages through its idle roller 207, with a Maltese cross wheel 208 carried by a shaft 209, which is in such manner subjected to an intermittent rotational movement. On the shaft 209 is keyed a pinion 210 which, engaging with a crown wheel 211 carried by the body of the wheel 185, determines, in its turn, an intermittent rotational movement of the wheel itself.

A pusher 212 and a companion 213 are situated in the range of the wheel 185, and more precisely are placed in horizontal alignment with the diametrically opposite apertures 192 and 191, and are subjected to a radical reciprocal and opposed-cyclical movement, starting from the internal edge of the compartments 186 unto the external edges.

In particular the pusher member 212 is supported, by means of an arm 214, from a protrusion 215 sliding on a guide rod 216 carried by the fixed body 217.

The reciprocal movement of the pusher 212 and thus that of the protrusion 215 rigid with it, are obtained by a lever 218 pivoted its lower section at an end, in 219, and restrained, by means of the pair of rollers 220 and 221, by a corresponding pair of profiles presented by a cam 222 revolving rigidly with the shaft 202. Said lever 218 is articulated, at its upper end and by the interposition of a link 223, to a pin 224 rigid with the protrusion 215. The longitudinal reciprocal movement of the protrusion 215 on the guide rod 216 is restrained by a roller 225 carried idle by the same protrusion 215 and slidingly engaged in the fixed horizontal guide 226. The protrusion 215 has a toothing or rack 227 on its upper side, by means of which it entrains in rotation a cogwheel 228, revolving about the shaft 229, which engages in turn with an overhanging rack 230, identical to the preceding rack, obtained on the lower section of a protrusion 231, which supports cantileverwise, through the arm 232, the companion member 213. In analogous manner to what has been seen previously, the protrusion 231 also slides horizontally on the fixed rod 233 and is constrained in its horizontal reciprocal movement by the roller 234 which slidingly engages in an horizontal guide slit 235. In such manner a contrary reciprocal movement of the pusher 212 and the companion member 213 is assured; this latter cooperates with the pusher 77 for the introduction of the packets, through the aperture 191, in the compartments

186 of the wheel 185, and the pusher 212 pushes the packets themselves, to the end of their transfer, out of the wheel 185, through the aperture 192, along the shaft 188c.

Once arrived there the packets are forwarded by a further pusher member 236 towards successive phases of the working, in an orthogonal direction to the previous direction of movement maintained along the conditioning line through the successive stations 78, 79, 80, and 184. To such purpose, on the shaft 12 is rigidly mounted a cogwheel 237 which engages with the wheel 238 attached to the shaft 239.

To the wheel 238 is constrained the big end 240 of a connecting rod 241 which, at its other end 242 is pivoted to a sleeve 243 to which is attached a horizontal rodlike element 244 sliding in the support 245.

At the end of said rodlike member 244 is attached the aforesaid pusher 236; it is thus clear that the pusher 236, activated by reciprocal movement, gathers at each stroke the successive packets at the exit from the wheel 185 and forwards them transversely, in particular towards the station for the application of the sealing tapes or sealing stamps, as will be described hereinafter.

A folder plate member 246 is situated in a plane substantially flush with one of the flanks of the compartment wheel 185, in the range of the area of entrance 191. Such member 246 is attached on the upper side to a rodlike member 247, and is subjected to a reciprocal movement in a vertical direction, owing to the engagement of a revolving roller 248, associated to said rodlike member 247, inside a groove 249 obtained in w disk cam 250 rigidly mounted on the shaft 202. The rod 247, in its vertical movement is constrained by the engagement of an idle roller 251 sliding inside the vertical guide 252. Underneath and in the plane of said folder 246 is provided the fixed checking member 253 (see FIG. 2) associated to the lower cover 188 and whose function will become more evident hereinafter.

The packet of cigarettes which, at the exit of the wheel 185 is pushed transversely by the pusher 236, intersects in its movement a station in which the application occurs of an individual sealing tape (not shown) which seals the opening of the packet itself, as shown in FIG. 3.

For such reason the packet passes between the prongs of a forked distributor 255 which is activated by reciprocal motion in a vertical direction. More precisely, as will now be described, the fork draws and entrains by suction at every upward stroke underneath the area of passage of the packet, a glued sealing tape 254 supplied by a distribution apparatus similar to that for the labels 172, and shown in detail in said U.S. Pat. Nos. 3,559,617 and 3,495,820.

The sealing tape is drawn and entrained so as to span the fork 255.

The fork 255, in its return stroke, comes in the range of the area of passage of the packets, so that when the packet itself, is pushed through the forked branches 255, the sealing tape is caused to lie on the opening of the packet where it is fixed. For achieving the desired vertical reciprocal movement the fork 255 is attached to the end of a hollow rodlike member 256 with which engages in 257 a link 258 constrained in 259 at the end of an oscillating lever 260 pivoted in 261 and constrained, by means of a revolving roller in 262 carried by said lever and a disk cam 263 rigidly mounted on a shaft 264. It is understood, that, in this manner, the lever 260, oscillating about the pin 261, subjects the fork 255 to the desired reciprocal movement. The motorization of the shaft 264 is determined by the engagement of a cogwheel 265, rigid with it, with a further wheel 266, which engages in turn with the wheel 204 carried by the shaft 205.

The successive sealing tapes arrive as has been said, from a distribution apparatus situated above the distributor fork 255 and are put in motion by a chain 267 which after having been returned from the chain wheels 268 and 269 engages with the chain wheel 270 rigidly mounted on the main shaft 12 of the machine. Such sealing tapes rhythmically removed one after the other are distributed in synchronism with the reciprocal

movement of the fork 255 and the end of the upward stroke of said fork, with a suction system: for such reason the branches of the fork 255 are hollow defining pipes communicating by means of hole 255a with the outside. At the opposite end the said pipes of the fork communicate with the inside of the hollow rod 256, which is placed in communication, intermittently, with a suction source, not shown. This is obtained by a distributor 271 which comprises substantially a rigid sleeve 272 and a hollow valve 273, slidably held inside said sleeve. At the closed end of the valve 273 is supported a revolving roller 274 which engages against an eccentric profile 275 rigidly mounted on the shaft 264. At the opposite end, a helical spring 276 is interposed between the valve itself and a body of the sleeve. In such manner the valve 273 is subjected to a reciprocal movement determined by the engagement with the eccentric profile 275, and in opposition with the spring 276. The inside of the valve 273 is in communication, through a pipe 277 with the suction source, while the hollow inside of the rod 256 communicates, through the union 278, with the inside of the sleeve 272 and then with the inside of the sleeve 273 through the radial apertures 279 presented by the walls of the valve itself in the range of an annular groove 280 communicating with the outside through the section of discharge pipe 281. Said apertures are in such manner periodically in the range of the outlet of the union sleeve 278, so as to put in communication, intermittently, through the hollow inside of the rod 256, the holes 255a of the fork 255 with the suction source.

It will consequently be evident that it is possible to produce the suction in the range of the holes 255a on the fork 255 is at the end of its vertical excursion, so that the sealing tape 254 will be entrained on this fork when descending from the distributing apparatus. Maintaining the suction through the holes 255a the sealing tape is entrained also during the downward stroke of the fork 255 until the branches of said fork are situated so as to span the the transverse journey of the packet of cigarettes. At this point, ceasing the suction through the holes 255a, the sealing tape 254 is abandoned in the moment in which the packet passes through the branches of the fork, so as to be entrained away.

The packet of cigarettes under the action of the pusher 236, after having passed the fork 255 is forwarded in the pipe 282 and exceed to spring nonreturn wedges 283, thus guaranteeing in every case the impossibility that the packet might move, even slightly, behind.

The said distributing apparatus for the sealing tapes 254 may be, for example, exactly similar to the distribution apparatus for labels 172 seen previously. Consequently it will comprise a hopper 284 (see FIG. 8), from the bottom of which the sealing tapes 254 are removed one by one, cyclically, by means of a cylindrical sector 255 activated by a rototranslational movement. The sector surface 285 is put into intermittent communication with a suction source by means of a distributor valve 286 activated by reciprocal motion. The sealing tapes, removed by suction, are forwarded to a gluer group comprising a tank 287 in which is contained the gluing material.

Said tank may rotate about a transverse shaft and inside it dips a glue roller 288, supported by the tank, which transmits the glue through a counterroller, not shown, onto the surface of the sealing tape in transit.

At the exit from the machine just described the packets of cigarettes, may be forwarded, by the same pusher 236, to possible stations for the drying of the glued areas. It is advantageous to such purpose to provide for the use of an apparatus of the type forming the subject of another patent application, by the same applicant, and comprises in substance housing columns inside which the packets are dried naturally, without the required use of thermal-radiant members.

On the shaft 205 of the cam or revolving drum 206 is rigidly mounted a cam 289 in whose groove 290 is engaged a roller 291 revolvably mounted about the pin 292 at the end of the lever 293 pivoted at its other end in 294 to the support 295

fixed to the framework of the machine. A pin 296 is attached at an intermediate point of the said lever 293, said pin being capable of cooperating with a widened section 297 presented at an end of a rod 298 to whose other end is connected a buffer 299 extending as a circular crown sector, behind and underneath the wheel 185 in the range of the plates 190 and whose function will be more evident hereinafter. Said buffer 299 is maintained guided in its movements by a guide pin 300.

As has been said in the beginning, the machine is provided with sensitive means 5, which define, in the succession of packets of cigarettes advancing intermittently, the batches of defective cigarettes which are consequently expelled before arriving at the successive conditioning stations.

In consequence it will occur that at the said stations there will be presented, between the successive advancing batches of cigarettes, a gap corresponding to the removed batch of cigarettes. In such case it is extremely advantageous to be able to temporarily halt the working of some of the apparatus, and especially the apparatus for distribution of the sections of tinfoil and the apparatus for the distribution of labels and sealing tapes.

This in order to prevent the possibility that damage or jamming might occur at the introduction in the operative cycle of pieces of packing material lacking the innate support provided by the batch of cigarettes, or anyway in order to avoid a useless waste of material. For such reason the apparatus for distribution of pieces of tinfoil 155 comprises, according to what has been described in detail in the corresponding patent application by the same applicant, a device of rapid disengagement which halts the entraining and advancing movement of the pieces of tinfoil inside said apparatus for the time of passage of the gap.

Such device is rendered operative when the signal transmitted by the sensors 5 suitably memorized determines the engagement of a pawl 301 in the groove of a cam 302 motorized by the main shaft 12. By means of this the disengagement occurs between the shaft 12 and the entraining members which stop.

In analogous manner, the apparatus for the distribution of labels 172 is provided with members which, controlled by the same signal issuing from the memory sensitized by the information sent by the sensors 5, locking the distribution of the labels for an interval of time or for a step, corresponding to the time of passage of the gap relative to the packet previously eliminated.

For such reason, since the removal of the labels occurs by a suction on the surface of the sector 174; said suction, which occurs cyclically, is sufficient to interrupt for a cycle, corresponding to the removal of a label, the communication with the suction source, so that the label relative to the gap will not be removed. That is, since the intermittent communication is provided by movable distributive valve, it is sufficient to cut off for a cycle the suction pipe 303, by means of an obturator (see FIG. 8). Moreover, it is also provided that the tank 180 may rotate about the shaft 181, pushed by an arm 305, causing the disengagement between the glue roller and the counterroller 183, so as also to prevent a useless distribution of gluing material during the halt phase.

Since the distribution of sealing tapes or sealing stamps occurs in perfectly corresponding manner to that of the labels, it is understood that, in relation to the passage of a gap, in the apparatus for the distribution of labels corresponding operations will have to occur both on the relative distributor means 268, by means of an obturator 396, for the interruption for cycle of the communication with the suction source for the corresponding period, or to determine the disengagement between the glue roller 288 and the fixed counterroller, through the rotation of the tank 287 containing the gluing material, by the operation of a pusher arm 307. The description of the working of the conditioning machine according to the invention will now follow with the hypothesis of regular working, and that is excluding the case in which one or more batches of cigarettes are formed in defective manner.

In regard to the formation of the batches of cigarettes of more than one superimposed layer and the collection inside the compartments 3 of the chain 4 advancing intermittently, reference is made to the patent application, already cited. Similarly reference is made to the patent applications for the definition of the detailed constructions and working relative to the operations of transfer of the batches of cigarettes from the compartments 3 to the pincers 8 of the wheel 9, said transfer being operated by the pusher 7; as well as, finally, to the further transfer of the batch of cigarettes operated by the same wheel 9. It is supposed, moreover, that in the case under consideration the sensitive members 5, having checked the regularity of the packets of cigarettes in transit in front of them, will not intervene with the various members influenced by it, so as not to disturb the normal working of the machine.

In the operations of the apparatus, when a single batch of cigarettes exits from the wheel 9, and more precisely from its pincers 8 which are in horizontal position and adjacent to the successive conditioning line, the formation of successive envelopes of the packet on the batch itself occurs as follows (see FIGS. 2 and 3): the group of cigarettes G, which in such positions have their front flank (with respect to the direction of advancement) adjacent to the pieces of tinfoil 155 coming from the relative distribution apparatus, is held, together with said piece of tinfoil 155, between the holding surfaces 72 and 72a of the translators 71 and 71a which, moving rigidly, force the foil and batch of cigarettes to pass through die plate 146 inserting it between the pairs of pincers 84, 85 and 84a, 85a of the station 78 (see FIG. 4). Supposing that, as has been said, on the surface of the piece of tinfoil 155 there are produced bending lines which allow the folding in a predetermined and suitable area, the sheet 155 in its passage through said die plate 146 is bent easily to a U, so that its edges, projecting, after the exit from the die plate, rearwards are to be layed on the upper and lower layers of the batch of cigarettes. Moreover the presence of the teeth 149, in concomitance with the existence of further lines of invitation to the folding, causes a first lap of the flank of the tinfoil turned in the direction of advancement, in the range of and against the two heads of the batch of cigarettes.

When the translators 71 and 71a, having passed through the aperture 152 of the die plate 146, are brought into the range of the station 78, the rod 66 halts, and with it stops the translator 71 flush with the cover 81, while the rod 66a and the translator 71a still proceed slightly so that the holding surfaces 72 and 72a separate giving up the batch of cigarettes. In synchronism with this movement, the plates 90 and 91 which, at the stopping of the introduction of the batch of cigarettes are slightly removed according to the direction of the shaft 49, so as to permit the entrance of the group itself into the station 78 (see also FIG. 10), reapproach bearing their sections or edges 92 and 93 on the outside flank of the batch of cigarettes maintained horizontal, flush with the vertical walls delimiting the semicylindrical cover 81 against the opposite ends of the same batch of cigarettes between the prongs of the said U formed from the folded piece of tinfoil, entraining in position the parts of tinfoil already folded on the ends of the preceding batch of cigarettes. Thus the batch of cigarettes becomes contained between the pairs of pincers 84, 85 and 84a, 85a, said plates 90 and 91 and the edges of these latter, without any stresses being exercised on them. At this point the bladed folder 31 rises folding the lower edge of the tinfoil bent to a U on the flank of the batch of cigarettes by the interposition of the edges 92 and 93. Then the rotation of the pairs of pincers 84, 85 and 84a, 85a begins and thus the rotation of the plates 90 and 91 rotating about the shaft 49 and the batch of cigarettes turns with them. At the commencement of such rotation the upper edge of the tinfoil is also folded on the flank of the batch of cigarettes above the section previously folded by the folder 31, by the edge of the cover 81. After having rotated for half a turn, the group of cigarettes is placed between the holding surfaces 75 and 75a of the pair of translators 73 and 73a, which, analogously to what has been seen

earlier, are presented in a first instant slightly spaced apart, so that the group of cigarettes may enter between them, and which close in synchronism with the aperture of the plates 90 and 91 in such manner as to extract the edges 92 and 93 from the tubular envelope of tinfoil thus formed (see station 78 in FIG. 2).

Thus the transfer of the batch of cigarettes occurs without any stress being exercised on them. The translators 73 and 73a transfer the batch of cigarettes towards the second station, 79, 10 forwarding the packet in formation to pass through the die plate 147, in which by means of the teeth 150 the folding of the second flank of the tinfoil is achieved in the range of and against the ends of the batch. The said translators 73 and 73a accompany the packet of cigarettes in formation until it is 15 penetrated inside the station 79 between the pairs of pincers 86, 87 and 86a, 87a and the plates 107 and 108, in horizontal position, are inserted between the protruding ends, beyond the ends of the batch and on both faces of the envelope, so as to support the packet delicately and without force.

20 In this position, the bladed folder 109 folds, with the interposition of the plate 108, on one of the ends of the packet one of the protruding wrapping ends. Then beginning the rotation of the pair of the pincers 86, 87 and 86a, 87a and the plates 107 and 108 about the shaft 53, the fixed folder 115 folds the second wrapping end on the same packet end above the first, so that, when the packet is presented, after such rotation, at the exit of the station 79, in diametrically opposite position, the folding of one of its bases is by this time complete. 25 Moreover at the completion of the semicircular rotation of the transfer, inside the station 79, one of the wrapping ends of the opposite packet end is in turn folded on the batch of cigarettes by means of the fixed folder 116 (see station 79 in FIG. 2).

30 The packet arriving in such position is placed between the pair of holding surfaces 76 and 76a of the translator members 74 and 74a and are forwarded towards the successive station 80, by these members.

In particular between the holding surface 76a and the 35 packet is interposed a label 172 designed to compose the visible layer of the packet itself and is supplied, has been seen, by 40 a suitable distributor apparatus. The whole, constituted of the packet and the label 172, which, as is known, is intended to wrap the packet laterally and in correspondence with a base, in its movement towards the station 80 is constrained to pass to a die plate 148, which causes the folding to a U of the label 45 172 about the packet, analogously to what has been seen for the piece of tinfoil. Furthermore, the presence of the tooth 151 causes the folding on the relative end of the packets, of one of the side section of the label projecting on either side of 50 the said end. Then the packet inside the station 80 between the pairs of pincers 88, 89 and 88a, 89a where, as in the previous station, the plates 118 and 119 are inserted between the protruding end or edge portions entraining in position the sections already folded. The folder 120 folds one of the edges of 55 the label on the flank of the packet while, as soon as the rotation of the pairs of pincers 88, 89 and 88a, 89a and the plates 118 and 119 begins about the shaft 54, the second edge of the label is also folded against the flank, at the moment in which it 60 engages with the semicylindrical cover 83 which slides flush with the rotary trajectory of the packet. The last wrapping end of the layer of tinfoil still open, is folded against the relative end of the packet by the fixed folder 117.

When the packet completes its semicircular rotation inside 65 the station 80, it is deposited on the bracket 188a and is forwarded by the pusher 77, cooperating with the companion 213, inside the station 184, and enters through the aperture 191 into one of the compartments 186 of the wheel 185. While the packet enters such compartment 186 by means of 70 the corresponding plate 190 which is inserted between the horizontal ends of the label in the range of the respective end of the packet, the other flank section of the label protruding on time complete. Moreover at the side of the packet end itself is folded on said end. At this point, the movable folder 246 75 folds, with the interposition of the plate 190, one of the

protruding wrapping ends on the said end of the packet; while the rotation of the wheel 185 is beginning about the shaft 187, the fixed folder 253 folds on the same end, above the wrapping end already folded, the other of said wrapping ends, so that, when the packet is presented after such rotation, at the exit from the station 184, in diametrically opposite position, the folding of the label on the bottom of the packet is complete (see FIG. 3). During such rotation, the said wrapping ends which, as previously indicated, have received the glue from the label distribution apparatus in the manner according to the corresponding patent application cited above, are subjected to a pressure by means of the action of the buffer 299 which at each step of advancement of the wheel 185 presses the wrapping ends themselves against the corresponding plate 190 thus facilitating the setting of the glue for the closure of the bottom of the packet.

The packet of cigarettes transferred in position diametrically opposite the wheel 185 is pushed by the pusher 212 so as to come out from the station 184 through the aperture 192, being put in the range of the line of action of the transverse pusher 236. This pusher pushes the packet at one of its bases until it is made to pass through the branches of the fork 255 which is, in this phase, in alignment with the trajectory of the packet, and which entrain by suction, spanning the branches, the sealing tape 254 removed from the specific apparatus. When ending the suction which entrains the sealing tape on the fork, the packet passes through the branches of the fork and entrains away the sealing tape, which, being suitable gened, is layed transversally on the end of the packet, sealing it.

In this manner the formation of the packet has been completed, in all its parts, about the batch of cigarettes.

It is understood that all the operations described, relative to conditioning of a batch of cigarettes, are repeated for all the batches formed upstream from the machine, and therefore the various members are given periodic intermittent movement, one of whose possible embodiments is shown in FIGS. 9, 9a, and 9b.

Till now reference has been made to the case of regular functioning without interruptions caused by the presence of a defective batch of cigarettes.

Now the succession of operations will be described which occur in the various parts of the machine when the presence of a defective batch of cigarettes is sensed at the entrance of the conditioning line.

As has been said when the sensors 5 check the presence of an incomplete batch of cigarettes, a batch comprising cigarettes not completely filled with tobacco, they send an impulse to a memory which then provides, in logical succession, to expell the defective batch and to control the various members in correspondence with which a gap is present, in the succession of packets advanced intermittently, relative to the expelled batch of cigarettes.

In FIG. 8 one of the possible electromechanical embodiments of such sequence of operations is diagrammatically shown. Indicated by reference numerals 308, 309, 310, 311, 312, and 313 are some cams rotated in synchronism and suitably displaced in phase with a period corresponding to the step of intermittent advance of the batches of cigarettes. In particular the cam 308 periodically enters into contact with the switch 314 relative to the connection circuit between the sensors 5 and the memory 315, cyclically determining the closing and opening of it. In analogous manner the cam 309 periodically engages with the switch 316 relative to the control circuit of the expeller 6, the cam 310 with the switch 317 relative to the stop control of the members for feeding the tin-foil to the machine, the cam 311 with the self-exciter switch 318 relative to the disengagement control of the glue roller of the apparatus for the distribution of labels, the cam 312 with the self-exciter switch 319 relative to the detachment control switch of the gluer member of the sealing tape distribution apparatus, and finally the lagging cam 313 with the switch 320 relative to the stop control circuit of the members for the feeding of the sealing tape.

Reference numerals 321 and 322 indicate two closing contacts, in parallel, controlled by the sensitive members 5, which close the circuit in the case of the signalling of a defective batch of cigarettes. Indicated with reference numeral 323 is a closing relay of the contacts 324 with 325, 326, 327, 328, 329, and 330 and an equal number of relays for the contacts 331, 332, 333, 334, and 335, 336, 337, and 338, respectively.

Reference numeral 315 indicate a memory of electromechanical type composed of a disk rotating intermittently or in step with each machine cycle corresponding to a turn of the main shaft 12 and presenting a plurality of peripheral sliding pegs 339 operable by a setting hammer 340. Such sliding pegs, when operated, as will be seen hereinafter, by said setting hammer are designed to cause the successive closure of the microswitches 341, 342, 343, 344, 345, and 346. Said microswitches are respectively inserted in the circuit which is fed by the transformer 347 and which is designed to control the expeller 6; in the control circuit which causes the operation of the interception member 304 of the pipe 303 in order to cause the halt of the suction to the members for the distribution of the label; in the control circuit of the tooth 301, which engaging in the cam 302, determines the halt of the feeding of pieces of tinfoil; in the control circuit of the arm 305 which causes the disengagement of the glue roller in said distribution apparatus for the labels; in the control circuit of the interception member 306 of the distributor 286 in order to interrupt the feeding of sealing tapes to the machine; and finally in the control circuit of the arm 307 which causes the disengagement of the glue roller in the same apparatus for the distribution of sealing tapes. The sequence and the working occur in the following manner: the cams 308, 309, 310, 311, 312, and 313 rotate with uniform motion closing at each turn the relative switches, with a period corresponding to the step of advancement of the successive batches of cigarettes; however, as long as the batches of cigarettes passing in front of the sensors 5 have no anomalies, the contacts 324 of the relay 323 remain open, so that the functioning of all members occurs regularly. When, however, it happens that one of the batches 35 of cigarettes is defective, the sensors 5 cause in per se known manner, the closure of the switches 321 or 322 or of both parallel between each other. This closure prearranges things, in manner such that at the successive closure of the contacts 314, the relay 323 is excited, causing the closure of the contacts 324. As a result of the the setting hammer member 340 is operated in manner such as to displace in its sliding seat the peg 339 which is presented in range with it after being controlled. In its rotary movement, such peg successively causes, that is at each step of the memory disk 315 corresponding to a machine cycle, the closure of the microswitches 341, 342, 343, 344, 345, and 346. The closure of the microswitch 341 causes the excitation of the relay 325 which closes the contacts 331. In this way the consent is given by which, as soon as the contacts 316 are also closed, by means of the cam 309, the expeller 6 will be operated. The operation of the expeller 6 causes the defective batch of cigarettes to be removed. Consequently in the succession of batches of cigarettes which advance from the conditioning line a gap is defined. In similar manner the closure of the microswitch causes the excitation of the relay 327 and the consequent closure of the contacts 333 so that the interception member 304 of the distributor 303 is controlled, halting the suction of the label. The closure of the microswitch 343, which occurs simultaneously with the closure of the microswitch 342, because of the different distance 50 from the removal point and the utilization point of the label and the tinfoil respectively, causes the excitation of the relay 326 and the closure of the contacts 332, so that as soon as the cam 310 closes the contacts 317, the pawl 301 is controlled to engage inside the cam 302 so as to halt the feeding of the pieces of tinfoil. The closure of the microswitch 344 causes the excitation of the relay 328 closing in such manner the contacts 334 and 335 of self-excitation of such relay 328 through the self-exciting contacts 318 by means of the cam 311. This causes the disengagement of the glue roller for the label from 55 the corresponding counterroller through the oscillation of the

70

75

tank caused by the member 305. The closure of the microswitch 345 causes the energizing of the relay 329 and defines the closure of the contacts 336, and the immediate control of the interception member 306 and thus the halt of the suction in the apparatus for the removal of the sealing tapes. Finally the closure of the microswitch 346, causes, as soon as the cam 313 closes the contacts 320, the energizing of the relay 330. As a result of this and of the closing of the contacts 338, the energizing of said relay 330 occurs through the self-exciter switch by means of the cam 312, while the closing of the contacts 337 causes disengagement of the glue roller from the corresponding counterroller of the said distribution apparatus for the sealing tapes by the oscillation of the same roller by means of the member 307. Naturally the described sequence is repeated for each defective batch of cigarettes.

FIGS. 9, 9a, and 9b show the relationships of phase-time between the various movement members, specified in the first left-hand column with the reference numerals attributed to them in the description.

For the realization of the diagrams of such figures it is undertaken to report in abscissa the phases relative to a single complete cycle, expressed in angles, from a value of 0°, conventionally indicating the beginning of the considered cycle, to a value of 360° constituting the end of the cycle. This in that all the members, by the fact of accomplishing periodic movements, are directly or indirectly connected to rotating members (cams, cranks, Maltese crosses). It is remembered, in this connection, that to each complete cycle there corresponds the formation of a batch of cigarettes in the area upstream from the line for conditioning them into packets.

The starting phase-time is common to all the drawings, and thus to equal angular values equal phase-times correspond. Hence it is evident that in a same cycle the various members act on different and successive batches of cigarettes.

The convention employed for the ordinates is as follows: A continuous line, expressed only in positive ordinate values (first quadrant), represents the qualitative progresses of the movements of those members subjected to translational movements or reciprocal angular oscillations. Hatched areas indicate the phases of movement of the members subjected to rotation. Crosshatched lines indicated the suction phases in the apparatus for the distribution of the labels and sealing tapes (the phases, that is, in which the relative distributor valves put the suction source in communication with the members for the removal of said labels and sealing tapes). A continuous line expressed in positive and negative ordinate values (first and fourth quadrants) indicates the times of opening and closing of the electrical contacts, assuming that the positive ordinates correspond to the phases of closure of the contacts, and the negative ordinates to the opening of the contacts.

It will be observed that the diagrams have also been introduced relative to those members already described in detail in other particular copending patent applications by the same applicant and which are only briefly indicated: this is justified by the fact that the machine, which is a whole complex whose functioning is assured by the coordination of the movements of all its members, requires the specification of all the phase relationships, which, in the limited ambit of the single particular cited patent applications are evident.

For the reading of FIGS. 9 and 9a it is specified that: the pusher which transfers the batches from the feeding hopper 1 to the chain conveyor 4, not shown in the drawings because it forms the object of the U.S. Pat. No. 3,520,394 and marked in the diagram of FIG. 9 with the reference numeral 358, completes a reciprocal translational movement controlled by a rod and crank connection, in which the active stroke is composed of the ascending section of the diagram; the chain conveyor 4 advances intermittently, controlled by Maltese cross members and the extension of the phase of rotation of the cross (and of the advance of the chain) is indicated by hatched areas; the pusher 7 translates reciprocally, controlled by a rod and crank connection, and its active stroke is composed by the ascending section of the diagram (upper dia-

gram); with this its translation comprises a reciprocal rotational movement (bottom diagram): the ordinates of the diagram express the angular excursion starting from the position of thrust (zero ordinate);

5 the element 10 effects a reciprocal translational movement in which the operative position is expressed by the ascending section and by the maximum ordinate of the diagram; the sensors 5 translate reciprocally and the active phase of their stroke is in the central ascending area of their diagram; 10 the expeller 6 translates reciprocally, when controlled by the sensors 5, and its active course is composed by the ascending section of the diagram; naturally the expulsion is operated in the considered cycle, on the batch of cigarettes controlled in the previous cycle, and successive to that which is simultaneously controlled by the sensor 5; the pincer wheel 9 rotates intermittently for the first half of the cycle, and remains stationary for the second half of it; the pincers 8 of the wheel 9 open and close alternately, controlled by the cams, and the diagram shows the amplitude of the mutual opening in ordinates.

For the structural and functional details of the aforementioned members reference is made to the relevant patent applications by the same applicant.

25 The folder 31, controlled by the cam 23, translates reciprocally, and the folding occurs in the rising section of the diagram;

the pushers 71, 73, and 74 pass from a position at the end of the return stroke (maximum ordinate of the diagram) to a position at the end of the operative stroke (transport phase) which, in the diagram, corresponds to the zero ordinate value; such movement is controlled by the cam 60; also the companions 71a, 73a, and 74a controlled by the cam 60a effect an analogous movement, but with a certain dis-

35 placement of phase in the region of the ends of the stroke, that is when the corresponding pairs of holding surfaces diverge in order to permit the introduction or the removal of successive batches of cigarettes; the plate or blade members 90 and 91 with edges 92 and 93, with the shaft 49 of the station 78, passing (first diagram) from a closed position during the transfer of the batch of cigarettes (maximum ordinate) to a position of mutual spacing in order to abandon the packet (zero ordinate);

45 simultaneously (second diagram) the same plate or blade members rotate for half a cycle, controlled by the Maltese cross 41, and they remain stopped for the remainder of the cycle;

the pairs of support plates 107, 108 and 118, 119 relative to 50 the shafts 53 and 54 of the stations 79 and 80, controlled by the Maltese cross 45 rotate in synchronism with the said plates 90 and 91; naturally the three successive pairs of plates transfer three distinct and successive batches of cigarettes; the folder 109 translates reciprocally, controlled by the cam 112, and the active phase of its stroke corresponds to the ascending section of the diagram;

55 the wheel 185, controlled by the Maltese cross 208, rotates intermittently, and in each cycle its angular advance corresponds to the angle contained between two successive compartments 186; the folder 120 of the label oscillates reciprocally, controlled by the cam 140; the folder 246 translates reciprocally, controlled by the cam 250 and the active phase of the folder corresponds to the ascending section of the dia-

60 gram; the companion 213 and the expeller 212 translate reciprocally, in synchronism and in contrast of phase, controlled by the cam 222: in the ascending section of the diagram occurs the expulsion of a packet of cigarettes by means of the member 212, and in the descendent section the accompaniment of a new packet into a compartment 186 of the wheel 185 by means of the member 213;

65 the pusher 236 translates reciprocally, controlled by the crank mechanism 238, 241, and effects the pushing operation in the period of the descending branch of the diagram;

the buffer 299 is moved reciprocally by the cam 289 and exercises its action during the period of the maximum ordinate section of the diagram;

the fork 255 for the transport of the successive sealing tapes translates reciprocally, controlled by the cam 263, and transfers the sealing tapes to the line of passage of the packet moved by the pusher 236 during its descending stroke (descendent branch of the diagram);

correspondingly to the removal and transfer of the sealing tape, the valve 273 effects the communication between the suction source and the branches of the fork (crosshatched diagram).

With regard to the apparatus for distribution of the pieces of tinfoil, the labels and the sealing tapes, in FIG. 9a are shown: the phases of cutting of the continuous strip of tinfoil into pieces by means of the cutting edges not shown and conventionally indicated in the diagram by reference numeral 359; the active phase of transport of the label by means of the sector 174, in concomittance with the suction which is exercised on the sector by means of the corresponding valve not shown in the drawing and conventionally indicated in the diagram by reference numeral 360, which, during this phase, maintains the suction source in communications with the sector itself.

With reference to the same cycle, the FIG. 9b shows the relationship of phase of the electromechanical members whose intervention is connected to the signaling of a batch of defective cigarettes by the sensors 5. In particular, in the diagrams are indicated, with the convention specified at the beginning, the phases of opening and closing of the microswitches controlled by the memory wheel 315, as well as those of the contacts controlled by the relative retarding cam.

It has been ascertained in practice that the machine for conditioning cigarettes into packets according to the invention perfectly achieves the predetermined objects, in particular in its practical embodiment high speed of functioning have been achieved, with a production of packets per unit time considerably superior to that of machines in common use in this field.

At the same time, the packets of cigarettes which are presented at the exit of the machine are all perfectly finished, without the presence of defective packets, either because of incomplete packets or because of cigarettes insufficiently filled with tobacco. And above all, and what is most important, the cigarettes themselves present, inside the packets, a perfect form and a raised standard of quality: this is due to the fact that, as has been seen, during their entire cycle of conditioning into packets, they are not in any way stressed in the direction of their minor resistance. Moreover in all those phases which occur in proximity or in the range of the end of the cigarettes and thus the ends of the packets, the forming operations of the envelopes never occur directly on the cigarette, but provision is made for the interposition, between the cigarettes and the packing material, of movable mandrels succeeding along the line of formation of the packets. Thus the fundamental result is achieved which, contrary to what generally occurs in the specified field of the conditioning of cigarettes into packets, the cigarettes never directly intervene to form or complete the support mandrel for the formation of the envelopes, so that they do not in any way undergo abnormal stresses which are converted into a deterioration of appearance, and crumpling of the cigarette papers.

The invention thus conceived is capable of numerous modifications and variations, all lying within the scope of the inventive concept. So for instance all those members and apparatus collateral to the formation proper of the envelopes of the batches of cigarettes may also be different from those shown. More particularly the system of feeding the batches of cigarettes to the conditioning line, the apparatus for the distribution of the pieces of tinfoil, the labels and the sealing tapes may be different, although particularly satisfactory results have been achieved with the devices and apparatuses indicated in the description. Analogously, the electrical diagram of the members controlled by the sensors have been

given at illustrative title, in order to indicate one of the numerous possible solutions. Moreover all the details may be substituted by other technically equivalent members, or integrated with others. So, for example, in the first phase of the folding of the tinfoil 155, that is during the passage through the die plate 146, a mechanism may be provided comprising two interparallel plates or blades capable of accompanying the batch of cigarettes with said tinfoil through said die plate and into the interior of the station 78 arranged in the range of the opposite end or head of the batch, in manner such that the folding of the tinfoil by means of the teeth 149 of the die plate 146 occurs on the free end of the aforesaid plate or blade members. One such device is shown by way of example in FIG. 13, in which said plates or blades are indicated with reference numeral 348. Each of said blades is carried at the end of a pin 349, carried in turn of a lever 350. At the other end of said pin 349 is connected an arm 351 carrying at its free end an idle roller 352 slidingly guided in the guide 353 attached to the framework of the machine, for example to the support 358 forming the support plane for the batches of cigarettes during their transfer from the station according to another patent application comprising the pincer wheel 9, to the station 78. The lever 50 is rigid with the shaft 354 carried revolvably by the framework of the machine and on which is also rigid the end of an arm 355 carrying at its other end an idle roller 356 cooperating in the groove of a control cam 357 rigidly mounted on the shaft 22 of the folder 31 seen previously.

In this manner the oscillations of the arm 355 by means of the control 357 cause the oscillation of the pair of levers 350 and thus a guided reciprocal movement of the above mentioned plates or blades 348 connected to said levers.

What I claim is:

1. An automatic machine for packaging cigarettes into packets, including members for arranging cigarettes in successive batches wherein they are superposed in parallel and aligned side by side, said machine comprising,

a plurality of pairs of translator members for supporting batches of cigarettes and cigarette package wrapping paper for movement with said machine, each said pair of members defining a pair of opposed, spaced, parallel surfaces aligned with the longitudinal axes of cigarettes in a batch of cigarettes held therebetween, means for moving said pairs of translator members perpendicularly to said axes, a plurality of pairs of rotatable support plates, each said pair of support plates defining a pair of opposed, spaced parallel surfaces aligned perpendicular to the axes of cigarettes of a batch therebetween and positionable within said machine to receive and hold a batch of cigarettes therebetween from one of said pairs of translator members, means for respectively moving each pair of support plates rotationally together about an axis of rotation normal to said support plates, paper-wrapping means including a plurality of first and second folding members, one pair of first folding members and one second folding member for each pair of support plates, each said pair of first folding members being disposed in parallel to receive a corresponding pair of said translator members therebetween and to engage the wrapping paper and fold the wrapping paper over portions of the ends of the batch of cigarettes moved with said translator members, and each second folding member being disposed adjacent a corresponding pair of said rotatable support plates to fold the wrapping paper over sides of the batch of cigarettes, parallel to the axes of the cigarettes when said cigarettes are held by said parallel plates.

2. The invention as set forth in claim 1, including means comprising a first and a second packaging station within said machine and each including a pair of said first folding members, and a third packaging station having only one of said first folding members; and each of said packaging stations having a pair of said translator members for moving a batch of cigarettes and a wrapping paper past said first folding members, a pair of said rotatable support plates for receiving

therebetween a batch of cigarettes from the said pair of said translator members, and a second folding member adjacent the said pair of rotatable support plates, and wherein said first and second stations comprise means for folding an inner wrapping about said batch of cigarettes, and said third 5 wrapping station comprises means for folding an outer wrapping about said batch of cigarettes.
